UNITED STATES PATENT OFFICE.

JOSEPH G. MAXWELL, OF BROOKLYN, NEW YORK.

REVERSING-GEAR FOR MULTIPLE-EXPANSION STEAM-ENGINES.

1,078,299.

Specification of Letters Patent.

Patented Nov. 11, 1913.

Application filed October 25, 1912. Serial No. 727,746.

To all whom it may concern:

Be it known that I, JOSEPH G. MAXWELL, a citizen of the United States of America, residing at Brooklyn, in the county of 5 Kings and State of New York, have invented certain new and useful Improvements in Reversing-Gear for Multiple-Expansion Steam-Engines, of which the following is a specification.

10 My invention relates to reversing gears for multiple expansion and compound steam engines and its object is to eliminate the complicated mass of machinery heretofore necessary and substitute therefor a simple, 15 compact, and efficient mechanism.

As showing a specific embodiment of my invention reference is made to the drawings forming part of the specification in which—

20 Figure 1 is a top plan view of the body of my reversing gear showing the high pressure eccentric attached. Fig. 2 is a view of the interior of the reversing cylinder with the fixed piston and shaft in section 25 to show the means of attaching the former. Fig. 3 is 120° section of the sleeve *b* showing the steam ducts. Fig. 4 is a side elevation of the steam chest showing the valve mechanism in dotted line. Fig. 5 is a plan 30 view of the contact face of the valve and Fig. 6 is a section on the line 4—4 of Fig. 5. Fig. 7 is a top plan view of the valve seat. Figs. 8, 9 and 10 are details of the low pressure eccentric. Fig. 11 is a side elevation 35 of my reverse gear attached to a compound engine. Fig. 12 is a rear elevation of the same showing the steam chest in position.

The following is a brief description of the drawings in which like characters 40 denote like parts.

A is the reversing cylinder containing the fixed piston *k* around which it rotates through an angle of 120°. It is closed by two cylinder heads *b* and *c* removably 45 mounted on the cylinder. The cylinder head *c* is made in one piece with the sleeve *c'* to which the high pressure eccentric *d* bearing the strap *d'* and rod *d''* is directly attached. The head *b* is made in one piece 50 with the sleeve *b'* which has a jacket *e* covering it. Within the sleeve *b'* are the grooves or passages *f* and *f'* which by means of the ducts *i* and *j* respectively convey the steam to the reversing gear. The piston *k* being fixed by means of the pin *l* to the

shaft *h*, the steam forcing against the partition *a'* causes the cylinder to rotate through an angle of 120° carrying with it the high pressure eccentric *d*. The cylinder *a* has a steam chest *r* connected by means 60 of the pipes *m* and *m'*. Steam entering the chest through the pipe *2* passes through the passage *u*, in the valve into the openings *w* and *w'* in the valve seat as may be directed by the operator by means of the shaft *t'*, 65 set into a boss on the valve *t* and joined by a set screw, at one end and having at the other the handle *t''*. If the handle be turned so the opening *u* in the valve *t* is over the opening *w* in the valve seat, the steam passes 70 through the valve at *u* into the seat at *w* and through the seat by means of the passage *w'* to the pipe *m* and into the passage *f* and so to the cylinder as described above. When the valve is in this position the steam 75 groove *v* connects the opening *w'* with the exhaust port *x* which it will be seen is much smaller than the inlet ports. Thus the steam already in the space, shown in Fig. 2 but not indicated by a character exhausting through the passage *j* is restricted at *x* and acts 80 as a cushion to prevent shock in reversing. The low pressure eccentric *z* carrying the strap *z'* and rod *z''* is self reversing having 85 a slot *z'* in which an enlargement or shoulder *h'* upon the shaft engages allowing it to rotate through an angle of 120°. It is held from slipping by plates *y* bolted upon the sides, and engaging the end of the shoulder *h'*. 90

The complete operation of the gear is as follows: Steam is admitted to the steam chest *r* by means of the pipe *2*. Its admission to the ports *m*, *m'* is governed by the long stemmed valve *t*. If steam is admitted to the port *m* it passes through the sleeve *e* into the peripheral groove *f* in the sleeve *b'*, thence through the passage *i* into the space *i'* in the cylinder *a*. The pressure of the steam (the piston *k* being fixed to the shaft) forces the cylinder *a* to rotate until the formerly disengaged wall of the piston engages the formerly disengaged wall of the cylinder partition, the rotation taking place through an angle of 120°. The high pressure cylinder being fixed to the cylinder *a*, by means of the head *c* and the sleeve *c'* rotates therewith and is swung into a reversed position. In this manner one cylinder (in a compound engine the high pres- 100 105 110

sure) is reversed. The other being provided with self reversing eccentrics may be reversed by admitting steam to the reversed cylinder and allowing the engine to run.

5 It will be seen by those skilled in the art that this device may be attached not only to any multiple expansion engine but to any engine having eccentrically operated valves and that many changes may be made without changing the letter of the invention.

10 Having now described my invention what I claim and desire to secure by Letters Patent is:

1. In a reversing gear for multiple expansion steam engines the combination of a high pressure eccentric, means for reversing same eccentric comprising a cylinder mounted on the shaft of said engine and adapted to rotate with the same, a pair of cylinder heads on said cylinder, a short sleeve cast in one piece with one of said cylinder heads and adapted to engage the high pressure eccentric, means for rotatably shifting said cylinder through an angle of about 120° with 20 relation to the shaft comprising a fixed piston and a partition within said cylinder means for admitting steam to the cylinder on either side of the piston so as to bring the formerly disengaged wall of said partition into contact with the formerly disengaged wall of the piston, means for preventing shock in the contact comprising a steam cushion formed by the reduction of the exhaust port thus restricting the escape of the 30 steam from the space in the cylinder and a self reversing low pressure eccentric substantially as described.

2. In a reversing gear for multiple expansion steam engines the combination of a high pressure eccentric means for reversing said eccentric comprising a cylinder mounted on the shaft of said engine and adapted to rotate with the same, a pair of cylinder heads on said cylinder, sleeves cast upon said cylinder heads means for attaching one of the sleeves to the high pressure eccentric, a cover on the other sleeve means for making said cover steam-tight, means for introducing steam to said second sleeve and means embodied in the sleeve for conducting said steam to the cylinder means for rotatably shifting said cylinder through an angle of 120° with relation to the shaft comprising a piston and a partition within said cylinder, means for fixing said piston to said shaft, comprising a pin extending into said piston and adapted to engage in said shaft and means for admitting said steam to the cylinder on either side of the piston so as to bring the formerly disengaged wall of said partition into contact with the formerly disengaged wall of the piston, means for preventing shock in the contact comprising a steam cushion formed by the reduction of the 40 exhaust port thus restricting the escape of the steam from the space in the cylinder and a self reversing low pressure eccentric substantially as described.

3. In the steam from the space in the cylinder and a self reversing low pressure eccentric substantially as described.

3. In a reversing gear for multiple expansion steam engines the combination of a high pressure eccentric means for reversing said eccentric comprising a cylinder mounted on the shaft of said engine and adapted to rotate with the same, a pair of cylinder heads on said cylinder sleeves cast upon said cylinder heads means for attaching one of said sleeves to the high pressure eccentric, means for introducing steam to said cylinder through the second sleeve comprising a pair of parallel grooves in said sleeve ports in said grooves, said ports connecting with passages leading to the cylinder, a cover for said second sleeve, means embodied in the sleeve for insulating said grooves, means for introducing steam to either of said grooves and connecting the other with the exhaust, means for rotatably shifting said cylinder through an angle of 120° with relation to the shaft comprising a piston and a partition within said cylinder, means for fixing said piston to said shaft comprising a pin extending into said piston and adapted to engage in said shaft, said passages entering the cylinder on either side of the piston so as to bring the formerly disengaged wall of said partition into contact with the formerly disengaged wall of the piston, means for preventing shock in the contact comprising a steam cushion formed by the reduction of the exhaust port thus restricting the escape of the steam from the space in the cylinder and a self reversing low pressure eccentric substantially as described.

4. In a reversing gear for multiple expansion steam engines the combination of a high pressure eccentric, means for reversing said eccentric comprising a cylinder mounted on the shaft of said engine and adapted to rotate with the same, a pair of cylinder heads on said cylinder sleeves cast upon said cylinder heads means for attaching one of said sleeves to the high pressure eccentric, means for introducing steam to said cylinder through the second sleeve comprising a pair of parallel grooves in said sleeve ports in said grooves, said ports connecting with passages leading to the cylinder, a cover for said second sleeve, means embodied in the sleeve for insulating said grooves, means for introducing steam to either of said grooves, and connecting the other with the exhaust comprising a steam chest, means for introducing steam thereto, a valve and a valve seat within said steam chest, a port extending through said valve and steam groove diametrically opposite said port and extending slightly past the center of contact face thereof, a pair of diametrically opposite inlet ports and a centrally located exhaust port in the valve seat, said exhaust port being smaller than

- 5 said inlet ports, means for connecting said inlet ports with the grooves, means for connecting the port in said valve with one of the inlet ports in which case said steam groove connects the second with the exhaust port, means for rotatably shifting said cylinder through an angle of 120° with relation to the shaft comprising a piston and a partition within said cylinder, means for fixing 10 said piston to said shaft comprising a pin extending into said piston, and adapted to engage in said shaft, said passages entering the cylinder on either side of the piston so as to bring the formerly disengaged wall of 15 said partition into contact with the formerly disengaged wall of the piston, means for preventing shock in the contact comprising a steam cushion formed by the reduction of the exhaust port thus restricting the escape of the steam from the space in the cylinder, 70 means for making the low pressure eccentric self reversing comprising a groove extending through 120° in the shaft-bearing face of said low pressure eccentric a key formed on said shaft and normally adapted to engage said eccentric and swing free through said groove to 120° when the engine is reversed and means for holding said eccentric from longitudinal movement on the shaft comprising a pair of plates bolted to said eccentric and adapted to engage the ends 75 of said key. 15
- 20 6. A reversing gear for steam engines having eccentrics, comprising a cylinder mounted on the eccentric bearing shaft of said engine and attached to one of said eccentrics and adapted to reverse the same, the remainder of said eccentrics being self reversing. 80
- 25 7. In a reversing gear for steam engines having eccentrics, the combination of a cylinder for reversing one of said eccentrics mounted on the eccentric bearing shaft of the engine and having its piston affixed thereto and self reversing eccentrics as described. 90
- 30 8. In a reversing gear for steam engines, having eccentrics the combination of means carried by the eccentric bearing shaft of the engine for reversing one of the eccentrics, with other eccentrics adapted to automatically shift on the shaft through an angle sufficient to reverse the same. 100
- 35 9. In a reversing gear for steam engines, having eccentrics the combination of one of the eccentrics of the engine, of a cylinder for reversing said eccentric mounted on the eccentric bearing shaft of the engine, and self reversing eccentrics as described. 105
- 40 10. A reversing gear for multiple expansion steam engines having eccentrics, comprising, the combination with the engine of a cylinder mounted on the eccentric bearing shaft of said engine adapted to reverse the high pressure eccentric thereof and self reversing low pressure eccentrics as described. 110
- 45 11. A reversing gear for steam engines having eccentrics comprising a cylinder mounted on the eccentric bearing shaft and attached to one of said eccentrics, means for shifting said cylinder with relation to said shaft through an angle sufficient to reverse said eccentric, the remainder of said eccentric being self reversing. 120
- 50 12. A reversing gear for steam engines having eccentrics, comprising a cylinder mounted on the eccentric bearing shaft of the engine, and attached to one of said eccentrics, means for shifting said cylinder 130
- 55 60 65

through an angle of 120° and thereby reversing said eccentric, comprising a partition and a piston within said cylinder, said piston being affixed to said shaft, one wall 5 of said piston normally engaging one wall of said partition, ports for said cylinder whereby steam may be introduced intermediate the engaged walls, of said piston and partition, whereby the normally disengaged 10 wall of the partition is brought into con-

tact with the normally disengaged wall of the piston, and self reversing eccentrics as described.

In testimony whereof I affix my signature in presence of two witnesses.

JOSEPH G. MAXWELL.
